UNITED STATES PATENT OFFICE.

WARREN T. REASER, OF FAIRMONT, NEBRASKA, ASSIGNOR TO THE ROUND VALVE COMPANY, OF CHICAGO, ILLINOIS.

ROLLING SUPPORT FOR SLIDE-VALVES.

SPECIFICATION forming part of Letters Patent No. 404,363, dated May 28, 1889.

Application filed December 31, 1888. Serial No. 295,092. (No model.)

To all whom it may concern:

Be it known that I, WARREN T. REASER, a citizen of the United States, residing at Fairmont, in the county of Fillmore and State 5 of Nebraska, have invented certain new and useful Improvements in Rolling Supports for Slide-Valves, of which the following is a specification.

The object of my invention is to obviate 10 the difficulties usually experienced in the use of this kind of rolling support for slide-valves by the flattening and compressing of the ends, causing a considerable friction and rapid wearing away of the teeth which hold them in 15 position and making it necessary to substitute new ones and to make an entire readjustment of the valve, causing more or less delay and loss of time, which can by the use of my invention be entirely overcome by substituting one 20 set of steel surface-pieces for another when worn out, thus making the supports as good as new without disturbing the adjustment of the valve in the least.

Referring to the accompanying drawings, 25 Figure 1 is a side elevation of a valve supported by anti-friction rollers cut away at the sides in the usual way and provided with my steel surface-protectors, the ends of the rolling supports being re-enforced by steel segments 30 and the valve-seat and cap being provided with steel rack-plates let into and flush with their surfaces, all these pieces being interchangeable, so as to facilitate the substituting of new pieces for the old ones when worn out. 35 Fig. 2 is a vertical section through the center of one of the rolling supports, showing the method of fastening the steel segments in place. Fig. 3 is a side view, and Fig. 5 a plan of a segment. Figs. 4 and 6 are a side view 40 and plan of the rack-plate.

In the drawings like letters indicate like parts in the several views.

A is the valve-seat, having the rack-plates *a* set in recesses provided for that purpose. 45 B are the rolling supports re-enforced by the segments *bb*.

The dotted lines C C show steam-ports.

D is the exhaust-port.

E is a cap bolted to the back of the valve

and resting on the rolling supports, relieving 50 the valve of friction contact with its seat.

To use my invention, the rolling supports and valve-seat and cap are provided with suitable recesses to receive the hardened steel segments *b*, and rack-plates *c*, which should be 55 made to a standard size, so as to be interchangeable and easily replaced when worn out.

I am aware that rolling supports have been used heretofore, but without being protected 60 from wear, as proposed by my invention. I am also aware that movable wearing-pieces have been used in mechanism at various times and do not therefore claim either of these devices, broadly, but limit my claims to the 65 special construction of parts hereinbefore described.

What I claim, and desire to secure by Letters Patent, is—

1. As an improvement in slide-valves for 70 steam-engines, the rolling supports for said valves recessed at their ends and provided with wearing-surfaces, and toothed segments *bb*, inserted in said recesses and adapted to be removed and replaced by others when worn, 75 substantially as set forth.

2. As an improvement in slide-valves for steam-engines, the removable rack-plates *a* and *c*, set into recesses formed in the valve-face *A* and cap *E*, said plates having plane 80 wearing-surfaces adapted to receive the wear of the rolling supports *B*, substantially as specified.

3. As an improvement in slide-valves for steam-engines, the rolling supports *B*, provided with removable segments *b*, in combination with a valve-face, *A*, the valve and cap *E*, said face and cap provided with removable toothed plates *a* and *c*, all arranged for joint operation in the manner and for the purpose 85 shown and described.

In testimony whereof I affix my signature in the presence of two witnesses.

WARREN T. REASER.
